UNITED STATES PATENT OFFICE

2,585,753

CENTRIFUGAL SEPARATOR

Herbert R. Drury, Waite Hill, Ohio

Application November 30, 1948, Serial No. 62,750

4 Claims. (Cl. 233—27)

1

This invention relates to centrifugal separating machines and more particularly to separating apparatus employed by miners in the separation of precious or highly valued metals from the substances bearing the metals and to such apparatus employing a rotating bowl for imparting centrifugal action to the substances under treatment.

It is among the objects of this invention to provide centrifugal separating apparatus whereby valuable metals may be efficiently and economically obtained from alluvium or gangue, particularly from such material containing black sand which has seriously interfered with separation as carried on in prior centrifugal concentrating bowls.

Another object of the present invention is to provide in a centrifugal bowl separator a concentrating pocket of novel design which will collect and retain the valuable concentrate and only a minimum of the black sand, gangue, etc. from which the concentrate is obtained.

Another object of the invention is to provide means in a centrifugal concentrating bowl which insures that the material as it passes the concentrating pocket is agitated and the heavier particles subjected to the maximum centrifugal force and the lighter gangue directed and discharged from the bowl.

A still further object of the invention is to provide in centrifugal separating apparatus a centrifugal bowl having a discharge opening of smaller diameter than the maximum diameter of the bowl and a concentrating pocket adjacent the discharge opening having a diameter greater than the maximum diameter of the bowl.

These and other objects and advantageous features of the invention not at this time more particularly pointed out will become more apparent as the nature of the invention is better understood from the following detailed description taken in conjunction with the accompanying drawings wherein like reference characters denote corresponding parts, and wherein:

Figure 1 is a fragmentary top plan view of a centrifugal separator embodying the present invention.

Figure 2 is a sectional view taken on the line 2—2 of Figure 1.

Figure 3 is an enlarged sectional detail view of the upper portion of the bowl including the concentrating pocket.

Figure 4 is a perspective view of one of the accelerator members associated with the concentrating pocket.

2

Figure 5 is a side elevational view of the device with certain parts omitted.

With reference to the accompanying drawings there is illustrated a centrifugal ore separating device embodying the teachings of the present invention and comprising a base frame 10 including side members 11 and end members 12 the adjacent ends of which are mitered and welded together to form a unit. Extending between the end members 12 are a pair of spaced angle irons 13 which receive a plate 14 positioned at the center of the frame 10. Mounted on the plate 14 and secured to the angle iron 13 is an upstanding base 15 formed with an internal axial bore 16.

Supported on the frame 10 is a hemispherical bowl 17 preferably made of aluminum or other non-magnetizing material, although the same may be made of iron, steel, plastic, or of molded hard rubber if desired, and formed with a hollow hub 18. A shaft 20 is press fitted into the hub 18 and is maintained therewithin by means of set screws 21. A collar 22 mounted on shaft 20 engages thrust bearing 19 mounted on the upper surface of base 15 and the lower end of the shaft projects into the bore 16 of the base.

The apparatus for rotating the bowl 17 is best illustrated in Figures 2 and 5 of the drawings and comprises a motor 23 mounted on a plate 24 supported upon a side frame member 11 and a transverse angle member 25 extending between the end frame members 12. Although a motor is illustrated in the drawing, any other suitable source of power may be employed depending upon the site where the device is to be used. The motor 23 drives a countershaft 26 supported in spaced bearing brackets 27, through a belt 28 connecting a pulley wheel 29 mounted on the motor shaft and a sheave 30 keyed to the end of countershaft 26. Extending between a sheave 31 on the countershaft 26 and a sheave 32 keyed to shaft 20 is a belt 33.

The bowl 17 is formed with a smooth interior surface and is provided with a vertical offset 34 adjacent its rim and an outwardly extending peripheral flange 35. Mounted on the peripheral flange 35 of the bowl is a concentrating pocket 36 the form and position of which forms an important part of this invention and is novel in that it employs both centrifugal force and gravity to concentrate the precious metals and collect the same within the pocket. The pocket 36 is formed with a horizontal bottom wall 37, adapted to seat upon the flange 35 and a depending flange 38 which is received within the offset 34 and thereby continues the inner wall of the bowl in

a smooth uninterrupted manner to the mouth of the pocket 36. Although the concentrating pocket 36 may be formed as an integral part of the bowl 17 or may be welded thereto I have illustrated the pocket as a separable part. A plurality of bolts 39 serve to secure the concentrating pocket in position upon the rim of the bowl. The outer circumferential wall of the pocket comprises a vertical portion 40 and an inwardly inclined portion 41, and is preferably spaced outwardly beyond the rim of the bowl. The top wall of the pocket comprises a horizontal portion 42 and an upwardly inclined portion 43. The upper wall of the pocket extends inwardly beyond the upper edge of the bowl and terminates in an outwardly curved discharge flange 44 of substantial width which extends horizontally beyond the outer extremity of the side wall of the pocket 36 and serves to direct and greatly stimulate the movement of tailings from the bowl. The top wall of the pocket defines a discharge opening for the bowl of smaller diameter than the maximum diameter of the bowl. The form and position of the concentrating pocket of the device is important in carrying out the objects of this invention in that both centrifugal force and gravity are employed to concentrate the valuable metal or mineral which is collected in its outer and lower diameter in the presence of black sand or magnetite. The amount of black sand or magnetite collected in the pocket is substantially limited due to the shape of the upper part of the pocket and the reduced diameter of the pocket at that point. The residue or tailings of sand, gravel, water and black sand being drawn up and outward by the centrifugal force and speedily discharged by the discharge flange 44.

In order to protect the inner surface of the bowl a renewable bowl liner 45 preferably molded from rubber or a suitable plastic is provided. Such a liner will greatly outwear the metallic bowl, can be economically replaced when worn out and serves to reduce the weight of the device. Drain plugs 46 are provided in the base of the bowl through which the concentrate may be removed from the bowl from time to time.

A circular launder 47 is coaxially positioned about the rim of the discharge flange 44 of the bowl. The launder 47 includes an outer cylindrical wall 48, an inner cylindrical wall 49 and a flat inclined bottom 50 thus forming an asymmetrical annular chamber. A rectangular discharge chute 51 is provided adjacent the lower portion of the bottom 50. The walls, bottom and chute are suitably secured together as by welding to form a completed unit. The launder is supported by a plurality of angle brackets 52 bolted or otherwise secured to members 53 extending upwardly from the base 10.

The bowl 17 is fed from a feed chute 54 which opens to the interior of the bowl adjacent the bottom thereof. A suitable bracket 55 supported by the members 53 serves to maintain the chute 54 in proper position within the bowl.

With reference to Figures 3 and 4 of the drawings, there is illustrated an attachment 57 which is positioned adjacent the mouth of the pocket 36 to facilitate the flow of the water and gravel past the concentrating pocket and to control such flow in a way to reduce the amount of black sand which may be retained in the pocket, thus enriching the concentrate and improving the conditions of concentration. The attachments are positioned at spaced points about the pocket and are adapted to rotate therewith and will be re-

ferred to hereinafter as accelerators. The accelerator 57 comprises a plate 58 adapted to be secured to the wall portion 43 of the pocket 36 by means of bolts 59. The plate 58 has angularly secured thereto an impeller 60. The impeller is preferably disposed at an angle of forty-five degrees to the axis of rotation of the bowl when mounted therein and when so positioned serves to act on the water and gravel passing the mouth of the concentrating pocket to direct it upwardly and outwardly onto the discharge flange 44 whereby it is conveyed to the launder 47.

Where there is a great amount of black sand or magnetite present in the placer sand, gravel or mine tailings, the accelerators are provided with a flow directing finger 61 welded or otherwise secured to the outer end of each impeller and extending downwardly and outwardly toward the concentrating pocket. The finger extends preferably at an angle of forty-five degrees to the radius of the bowl at that point and the flat side of the finger is inclined at an angle of forty-five degrees to the direction of rotation. The finger serves to interrupt the upward flow of material along the inner surface of the bowl, agitate the same and direct it into the mouth of the pocket.

In using the device the gangue or conglomeration of various metallic substances and associated substances, preferably in a finely divided state and mixed with sufficient water to form a pulp is introduced into the bowl 17 through the feed chute 54 and deposited in the bottom of the bowl. The bowl is then rotated so as to cause the mixture to travel outwardly and upwardly over the interior surface of the liner 45. I have found that where a bowl with a diameter of thirty-six inches is used a speed of about one hundred eighty R. P. M. is preferable. The rotation of the bowl creates a centrifugal force which acts upon the mixture and its contained solids as it moves upwardly along the smooth interior surface of the bowl causing the heavy desirable mineral particles to be forced further outwardly than the lighter particles thereby becoming "classified" as the mixture reaches the pocket. Due to the smooth surface of the bowl the contents never reaches the speed of the bowl, there being considerable slippage between the contents and the wall of the bowl. I have found that the contents of the bowl reaches its maximum rotative speed at a point adjacent the mouth of the concentrating pocket which is about two-thirds as great as the speed of the bowl. The accelerators 57 located at spaced points around the bowl immediately above the pocket revolve at a speed greater than the speed of the contents, thus creating a positive action upon the rising contents of the bowl by first creating a secondary flow of the contents into the pocket in addition to the action of centrifugal force and then creating an accelerated movement of the contents upwardly after passing the pocket, and thus clearing away any excess substance from the pocket where it is picked up by flange 44 and directed out of the bowl into the launder. The foregoing action continues until a considerable amount of concentrate has accumulated in the pocket, at which time the feed of solid substance is first stopped, and then the flow of water is cut off, leaving the bowl clean but with the concentrate of heavy metal and some sand and black sand in the pocket. The rotation of the bowl is stopped and the pocket washed out and drained into a suitable receptacle through the drain plugs 46.

Having thus described my invention so that

those skilled in the art may practice the same, what I desire to obtain by Letters Patent is defined in the appended claims.

I claim:

1. A centrifugal separator comprising a substantially hemispherical bowl having a smooth renewable liner, means for rotating said bowl about a vertical axis, a circumferential concentrating pocket mounted on the rim of said bowl and opening inwardly thereof, said pocket having upper and lower horizontal walls and a circumferential wall positioned outwardly of the rim of the bowl, the upper wall extending inwardly of the rim of the bowl, and a plurality of accelerators mounted on the inner extremity of the upper wall of said pocket and positioned adjacent the mouth of the pocket, said accelerators having a portion extending downwardly and outwardly toward the mouth of the pocket whereby material moving upwardly along the internal wall of said bowl will be interrupted and directed into said pocket.

2. A centrifugal separator comprising a substantially hemispherical bowl having a smooth renewable liner, means for rotating said bowl about a vertical axis, a circumferential concentrating pocket mounted on the rim of said bowl and opening inwardly thereof, said pocket having upper and lower horizontal walls connected by a circumferential wall positioned outwardly of the rim of the bowl, and a plurality of accelerators mounted on the upper wall of said pocket inwardly of the inner surface of the rim of the bowl and positioned adjacent the mouth of the pocket, said accelerators having one portion extending downwardly and outwardly toward the mouth of the pocket whereby material moving upwardly along the internal wall of said bowl will be interrupted and directed into said pocket and a second portion extending inwardly and downwardly and serving to direct material passing from the mouth of the pocket on to said discharge flange.

3. A centrifugal separator comprising a substantially hemispherical bowl having an outwardly extending flange formed on the rim thereof, means for rotating said bowl about a vertical axis, a concentrating pocket mounted on the flange of said bowl, said pocket being formed with a circumferential wall spaced outwardly beyond the rim of said bowl and a wall spaced from said

flange extending perpendicular to the axis of rotation of the bowl from said circumferential wall to a point spaced inwardly of the upper edge of the bowl and terminating in a reversely extending discharge flange, and a plurality of accelerators mounted on the inner extremity of said wall of said pocket and positioned adjacent the mouth of said pocket, said accelerators having one portion extending downwardly and outwardly toward the mouth of the pocket whereby material moving upwardly along the internal wall of said bowl will be interrupted and directed into said pocket.

4. A centrifugal separator comprising a substantially hemispherical bowl having a smooth renewable liner, means for rotating said bowl about a vertical axis, a concentrating pocket mounted on the flange of said bowl, said pocket having a circumferential wall spaced outwardly beyond the rim of said bowl and a horizontal wall spaced from said flange projecting inwardly of the upper edge of the bowl and terminating in a reversely extending discharge flange, and a plurality of accelerators carried by said pocket and positioned adjacent the mouth thereof, said accelerators having one portion extending downwardly and outwardly toward the mouth of the pocket whereby material moving upwardly along the internal wall of said bowl will be interrupted and directed into said pocket, and a second portion extending inwardly and downwardly and serving to direct material passing from the mouth of the pocket on to said discharge flange.
